UNITED STATES PATENT OFFICE.

AMOS G. FITZ, OF AUBURN, MAINE, ASSIGNOR TO FITZ DOUBLE PIVOT LAST COMPANY, OF AUBURN, MAINE, A CORPORATION OF MAINE.

LAST.

No. 909,388.

Specification of Letters Patent. Patented Jan. 12, 1909.

Application filed November 2, 1907. Serial No. 400,370.

To all whom it may concern:

Be it known that I, Amos G. Fitz, a citizen of the United States, and a resident of Auburn, in the county of Androscoggin and 5 State of Maine, have invented new and useful Improvements in Lasts, of which the following is a specification.

My invention relates to improvements in lasts and more particularly to solid lasts 10 which are divided transversely by lines of cut which permits the heel part to move upwardly and forwardly relative to the fore part for the purpose of shortening the last.

The invention consists in means for locking 15 the parts of the last in both extended and shortened positions.

In the drawings herewith accompanying, I have shown several embodiments of my invention.

20 Figure 1 is a longitudinal vertical sectional view of a last having one form of my invention applied thereto; Fig. 2 is a perspective view of the locking device shown in Fig. 1; Fig. 3 is a longitudinal vertical 25 sectional view of a portion of a last showing a different embodiment of my invention; Fig. 4 is an elevation of a portion of a last, parts broken out, showing a last with my improvement therein in locked shortened 30 position; Fig. 5 is a longitudinal vertical sectional view of a different form of my invention; Fig. 6 is a side elevation, parts broken out, showing a different form of my 35 invention; Fig. 7 is a perspective view of the locking device shown in Fig. 6.

In said drawings A represents the fore part, B the heel part, C the line of division of a solid last. The adjacent ends of the last are provided with kerfs D and E respectively in which are pivotally mounted 40 one or more bonding links F. Pivotally mounted in a recess H in the heel part is a locking device G. The upper end of the locking device is provided with a lug I adapted to have locking engagement with the fore part of the last.

I have shown various ways in which the locking device may engage the fore part. In 50 Fig. 1 the lug takes into a recess J in the fore part. In Fig. 3 the lug takes into the recess, but engages a wear pin K inserted just above the recess. In these cases the lug is slightly curved downwardly and when moved into shortened relation locks over the 55 top of the last holding the parts rigidly in

shortened relation as shown in Fig. 4. In these cases a coil spring L is inserted in the heel part and presses constantly against the locking device causing it to lock automatically and to hold it yieldingly against accidental displacement. To unlock the parts of the last draw the locking device back by pressure on the fingerhold M until the lug is disengaged when the parts of the last may be moved one relative to the other.

60 In Fig. 5 I have shown a form of my invention, in which the locking device consists of a bar N mounted in a recess O near the bottom of the last and provided with a spring coil P and with a shoulder Q adapted to engage a stop R on the fore part of the last.

In Figs. 6 and 7 I have shown a locking device having shoulders S adapted to engage pins S' projecting beyond the rear 75 face of the fore part. In this case the locking bar is provided midway its length with a recess V which gives entrance to the pins S' when the heel part is curved upwardly relative to the fore part so that it will permit the locking device to rest closely upon the rear face of the fore part. In all cases the locking device is operated manually by pressure upon the finger-hold. The locking bar is preferably mounted in the heel part 80 above the bottom and extends across the line of division when in operative position.

85 The advantages of my improved device are that it is adapted for use in a solid last. It is simple in structure, easily assembled and 90 operates automatically to lock the parts of the last together.

Having thus described my invention and its use I claim:

95 1. In a two part solid last divided transversely and having a recess extending thereto from the top, a vertically positioned rigid locking lever pivotally mounted in the heel part in said recess and adapted to have locking engagement with the fore part said 100 lever terminating outside the last in a finger hold and means tending constantly to hold said locking lever in locked engagement.

105 2. In a two part solid last divided transversely and having a recess extending thereto from the top, a vertically positioned rigid locking lever pivotally mounted in the heel part in said recess at a point spaced apart from the bottom and adapted to have locking engagement with the fore part said 110

lever terminating outside the last in a finger hold and means tending constantly to hold said locking lever in locked engagement.

3. In a two part solid last divided transversely and having a recess extending into it from the top and a stop in the rear face of the fore part; a vertically positioned rigid locking lever pivotally mounted in the heel part in said recess and terminating outside the last in a finger hold, a shoulder on said lever adapted to engage said stop and

a spring tending constantly to force said lever forward into engagement with said fore part.

In testimony whereof, I have signed my name to this specification in presence of two subscribing witnesses this twenty-ninth day of October, A. D. 1907.

AMOS G. FITZ.

In presence of—

JOHN A. MORRILL,
H. E. DUSTON.
